UNITED STATES PATENT OFFICE.

WARREN M. OSBORN, OF CHICAGO, ILLINOIS, ASSIGNOR TO CHICAGO MALLEABLE CASTINGS COMPANY, OF WEST PULLMAN, CHICAGO, ILLINOIS, A CORPORATION OF ILLINOIS.

RAIL-ANCHOR PLATE.

Application filed March 3, 1924. Serial No. 696,427.

To all whom it may concern:

Be it known that I, WARREN M. OSBORN, a citizen of the United States, residing at Chicago, in the county of Cook, State of Illinois, having invented certain new and useful Improvements in Rail-Anchor Plates, do hereby declare that the following is a full, clear, and exact description of the same.

My invention relates to improvements in tie plate structures for anchoring railway rails, and its object is to provide a novel and useful organization which locks the rail to the tie-plate in an improved manner.

The invention consists in the matters hereinafter described and then pointed out in the claims.

In the accompanying drawing, Fig. 1 is a perspective view of the plate; Fig. 2 is a similar view of the clip, and Fig. 3 is a view 20 in cross-section on the line 3-3 of Fig. 1 with the rail and a portion of the underlying tie added and with a clip in place on the plate.

In the drawing the reference letter A represents the head of a rail, B its base, C the web uniting the head and base, and D the tie.

The plate 1 is provided near one side with a shoulder 2 for the rail-base which carries 30 at its upper face a series of integral heavy ribs 3 spaced apart along its length and rising above it and overhanging the top edge of the rail-base when the latter is assembled on a tie-plate. The plate is provided with 35 spike-holes 4 for the spike 5 outside the line of the shoulder 2 and between the ribs 3, and the central rib has a threaded opening to receive a set-screw 6 which bears upon the rail-base to clamp it on the plate. The lower 40 faces of the overhanging ribs 3 are faced off to the contour of the rail-base which makes a driving fit between the ribs and the plate 1.

The opposite side of the plate 1 is provided with elongated spike-holes 7, and beyond each of these holes and spaced away from its outer end the plate is provided on its upper face with a shoulder 8 having an inwardly inclined inner face 9. The plate is provided on its under face with a recess 10 extending from the inner end of each spike-hole 7 toward its center and of the same width as the spike-hole and terminating in an inner shoulder 11. The spike-holes 7 receive clips that interlock with the rail-base 50 B and tie plate 1 and are heeled up by the

shoulders 8 to wedge the opposite side of the rail-base in position under the ribs 3. The clips are made of metal having a substantially rectangular body 12 constructed to overlie a spike-hole 7 and provided at its 60 inner edge with a depending lug 13 to abut against the rail-base and inner end of the spike-hole 7. The inner portion of the body 12 is provided with an upper inwardly directed flange 14 to overlie the rail-base, and 65 with an inwardly directed lower wing 15 to underlie the inner end of the spike-hole and seat in the recess 10 with its inner end against the shoulder 11. The wing and flange are in the same vertical plane to form 70 a pocket or seat for the edge of the plate and rail-base, the flange being beveled on its under face to fit the inclination of the base, and the lower face of the wing 15 being flush 75 with the lower face of the plate. The lower outer part of the body is thickened transversely and beveled or rounded as at 16 to wedge against the shoulder 8, and its upper end is provided with an inclined or beveled heeling-lug 17 for the head of the spike 18. 80 The holes 19 for the spikes 18 are outside the depending lugs 13 and have their outer walls in extension of the lugs 17.

In practice, an edge of the rail-base is 85 assembled to place under the overhanging ends of the ribs 3, and the clips are assembled on the plate on the opposite side of the rail-base, the wings being passed down through the elongated spike-holes of the plate; the clips are then moved inwardly 90 toward the rail so that their flanges 14 overlie the rail-base and their wings 15 underlie the inner ends of the spike-holes, and when the spikes 18 are driven to place on the ties they force the clips down on the inclined 95 faces of the shoulders 8 to crowd the clips into place and seat their wings in the recesses in the under faces of the plates and the lugs 17 heel-up the spike-heads so that they are not forced outwardly by the lateral thrusts 100 of the rail and the usual throat-cutting of the spikes is obviated. The flanges and wings of the clips interlock the plates and rail-bases together so that the plates are anchored to the rail, and the clips hold the 105 opposite side of the rail-base in its drive-fit engagement with the overhanging ends of the ribs 3. The clips thus interact with the ribs as they hold the rail under the ribs without putting the side stresses or lateral 110

thrusts of the rail on the spikes. As the screw 6 is set down on the rail base it is advantageous to have spaced or separate overhanging ribs instead of a single flange 5 extending the width of the plate, as in the former case the lifting action of the screw is confined to the central rib and will have no effect on the end ribs, whereas with a full or single flange this lifting action affects the 10 flange for its entire length and loosens its grip on the rail and the drive fit of the rail base between the flange and plate is relaxed.

I claim:

1. A device of the class described comprising a plate having an elongated spike-hole 15 in one of its sides and a recess in its under face in line with the inner end of said spike-hole, an inclined shoulder adjacent the outer end of said spike-hole, an abutment on the 20 opposite side of said plate provided with a plurality of spaced overhanging ribs, a clip constructed to engage said shoulder and having a spike-hole and an overhanging flange for one side of a rail-base and an inner de- 25 pending lug in the inner portion of said plate spike-hole, an inwardly extending wing at the lower end of the lug constructed to seat in said recess, and a heel-ing-lug in alinement with the outer end of the clip 30 spike-hole.
2. A device of the class described comprising a plate having an elongated spike-hole 35 in one of its sides and a recess in its under face in line with the inner end of said spike-hole, an inclined shoulder adjacent the outer end of said spike-hole, an abutment on the 40 opposite side of said plate provided with a plurality of spaced overhanging ribs, the center rib having a threaded opening, a set-screw engaging said opening, a clip constructed to wedge on said shoulder and having a spike-hole and an overhanging flange

for one side of a rail-base, a depending lug in the inner end of the hole in the plate, an inwardly extending wing at the lower end of the lug underlying the plate, and a spike-heeling lug in alinement with the outer end of said clip spike-hole. 45

3. A device of the class described comprising a plate having elongated spike-holes in 50 one of its sides, inclined shoulders adjacent the outer ends of said spike-holes, an abutment on the opposite side of said plate provided with a plurality of spaced overhanging ribs constructed to make a driving fit 55 with the side of a rail-base and arranged in staggered relation transversely of the plate with respect to said spike-holes, and clips constructed to wedge on said shoulders and each having a spike-hole, an overhanging flange bearing on the other side of the rail-base, a depending lug in the inner end of the hole in the plate, and an inwardly extending wing at the lower end of the lug interlocking 60 with the plate. 65

4. A device of the class described comprising a plate having an elongated spike-hole 70 in one of its sides, an inclined shoulder adjacent the outer end of said spike-hole, an abutment on the opposite side of said plate provided with a projection overhanging one side of a rail-base and having a threaded opening, a set-screw engaging said opening, a clip constructed to engage said shoulder and having a spike-hole and an overhanging 75 flange bearing on the other side of the rail-base and an inner depending lug in the inner portion of said plate spike-hole, and an inwardly extending wing at the lower end of the lug interlocking with the plate. 80

In testimony whereof I, hereto affix my signature.

WARREN M. OSBORN.
